UNITED STATES PATENT OFFICE.

GORDON ASTON, OF GRIMSBY, ENGLAND.

BICYCLE-SUPPORT.

SPECIFICATION forming part of Letters Patent No. 642,062, dated January 30, 1900.

Application filed October 25, 1897. Serial No. 656,353. (No model.)

To all whom it may concern:

Be it known that I, GORDON ASTON, a subject of the Queen of Great Britain and Ireland, residing at 192 Convamore road, Grimsby, in the county of Lincoln, England, have invented a certain new and useful Improvement in Bicycle-Supports, (for which I have obtained a patent in Great Britain, No. 28,384, bearing date December 11, 1896,) of which the following is a specification.

This invention relates to an improved support or prop for holding bicycles in an erect position when at rest upon roadways or in show-rooms or such like places.

15 The improved support is so constructed as to appear a part of the frame of the machine when not in use, for which purpose it is made of semicircular shape in cross-section, thus forming a half-tube, which fits closely around 20 or embraces one side of the tubular frame when in its raised position. This support is pivoted to an adjustable or hinged ring clamped to the frame at any required height, and its pivotal pin is fitted with a coiled spring 25 for forcing down and holding the support rigidly in its lowered position. The said half-tube or support is formed at its outer end with teeth or serrations for causing it to grip the ground, and it is kept in its raised position 30 by means of a spring lock or catch forming part of a hinged ring, which is clamped to the upper horizontal tube of the frame in such a manner that the locking-bolt engages with the said teeth or serrations when the 35 support is in its raised position and locks the same in such position.

In order to clearly understand my invention, reference is had to the accompanying sheet of drawings, in which—

40 Figure 1 is a side elevation of a bicycle-frame with the improved support attached. Fig. 2 is an elevation to an enlarged scale of the support. Fig. 3 is a view at right angles to the same; and Fig. 4 is plan thereof, the 45 support being in each view shown in its lowered or open position. Fig. 5 is a view to a larger scale of the locking device, and Fig. 6 is an end view of the same.

50 *a* is a support or prop of semicircular cross-section, so as to fit compactly against the tube *f* of the frame of the machine when raised

and locked in its closed position, thus appearing to constitute a part of the said frame. The support *a* is pivoted to a ring *b*, which is hinged at *b'* and clamped by the screw *b*² to 55 the tube *f* of the frame, the ring *b* being formed with lugs *b*³, to which the arms *a'* of the support *a* are pivoted by the pin *c*.

The pin *c* is fitted with the coiled spring *c'*, tending to open out the support when unlocked and hold it rigidly in its lowered position, as shown in dotted lines in Fig. 1.

The support is kept in its raised position by the lock or catch *d*, Fig. 5, carried by the projecting portion *d'* of the ring *e*. The said 65 ring is hinged at *e'*, as shown in Fig. 6, and clamped to the horizontal tube *f'* of the frame by the screw *e*². The catch *d* is fitted with a spring for keeping it in its locked position and is formed with a curved end or handle *d*² 70 for unlocking or drawing it back by hand.

The end of the support *a* is formed with teeth or serrations *a*² for causing it to take a firm foothold upon the ground and also for affording a means for locking the support by 75 reason of the spring catch or lock engaging therewith.

Having now fully described the nature of my said invention, what I claim, and desire to 80 secure by Letters Patent, is—

In a support for bicycles the combination of a prop *a* of semicircular cross-section and formed with arms *a'* pivoted by the pin *c* to the lugs *b*³ formed on the ring *b* hinged at *b'* and clamped to the frame *f* of the machine by 85 the screw *b*², the coiled spring *c'* fitted to the pin *c* for holding the prop rigidly in its lowered position, and the spring-catch *d* formed with a handle *d*², and carried by the ring *e* which is hinged at *e'* and clamped to the tube 90 *f'* of the frame of machine by the screw *e*², the spring-catch *d* engaging with the teeth or serrations *a*² formed at the outer end or bottom of the prop *a* for keeping the latter in its raised position when out of use, substantially 95 as described.

In witness whereof I have hereunto set my hand in the presence of two witnesses.

GORDON ASTON.
